BOWLING PIN REMOVING APPARATUS

Morehead Patterson, New York, and Charles E. Schon, West Hempstead, N.Y., assignors to American Machine & Foundry Company, a corporation of New Jersey

Filed July 7, 1955, Ser. No. 520,403

20 Claims. (Cl. 273—43)

This invention relates to bowling pin spotting machines, and more particularly to improvements in mechanism for removing fallen pins or deadwood from a bowling alley or the gutters thereof without disturbing standing pins which are to remain on a bowling alley for further play.

Our invention is adapted for use with automatic bowling pin spotting machines, such for example as shown in Rundell Patent 2,388,707, Frye Patent 2,707,707, and any other type of bowling pin spotting machine or installation with which it can be adapted for use.

In the game of bowling, ten bowling pins are usually spotted on the bed of a bowling alley in triangular arrangement with the apex of the triangle nearest the bowler. Because of this arrangement, as the result of rolling of a ball, the front pins or front rows of pins are most likely to be knocked down.

Our invention takes into consideration the fact that when the front rows of pins or pins in the front rows are knocked down, if such pins lie on the alley, they can be moved forwardly or transversely away from standing pins with a minimum of obstruction or substantially no obstruction by standing pins for delivery into the gutters of a bowling alley, where by suitable means, such as conveyor belts in the gutters, they are delivered into the pit of the bowling alley where suitable pin handling mechanism conveys them to the pin spotter for further use in playing the game.

In accordance with the invention, we provide means for positively engaging the heads of standing pins in order to hold each standing pin in the exact position it occupied after the throwing of a ball, and provide means operative while pins are so held for moving any deadwood or fallen pins forwardly away from such standing pins with a minimum of effort so that they can be displaced directly into the gutters of the bowling alley as the result of the movement of the pin removing means, or can be delivered into the range of operation of pin handling devices which move them from the alley into the gutters where suitable means such as belt conveyors or pushers can travel them rearwardly into the pit for further use in playing the game. After the removal of deadwood or fallen pins, the mechanism which clamped or held standing pins on the alley is raised thereabove so that the play of the game can continue according to normal procedure.

It is an object of our invention to provide means for holding on-spot or off-spot standing pins remaining on a bowling alley after the throwing of a ball against displacement from their respective positions or being knocked over, and to effect the positive movement of deadwood or fallen pins in a direction away from the pit of a bowling alley such that there will be substantially no obstruction to the movement of such fallen pins whereby they can be handled rapidly and efficiently in their delivery to the pit of a bowling alley for return to the pin spotter.

It is a further object of our invention to provide im-

2

proved mechanism for removing deadwood or fallen pins from the playing deck of a bowling alley after a ball is rolled without the necessity of lifting standing pins prior to the removal of fallen pins therefrom.

It is a further object of the invention to take advantage of the space left by fallen pins in the front portion of the pin supporting bed of a bowling alley such that such fallen pins may be moved with a minimum of effort and obstruction to a point of discharge from the alley bed and delivered to the pit for further handling in playing the game.

The invention is also characterized by the provision of means for clamping or firmly securing standing pins in their respective on or off-spot playing positions after the rolling of each ball of a frame, except the last ball thereof, and the provision of means for moving any fallen pins in a direction away from the pit of the alley, and clear of standing pins positively held on the alley in order that a minimum of obstruction or substantially no obstruction can occur to prevent the free movement of such fallen pins off the alley bed for ultimate delivery into the pit and return to the pin spotter.

In one form of the invention, there is provided a system comprising spaced parallel pushers having resilient or flexible pin engaging and pushing members which move fallen pins forwardly between and past standing pins, the latter being clamped on the alley by suitable means engaging the heads thereof. We have found that with mechanism embodying our invention, all deadwood or fallen pins can be separated from standing pins and removed from the alley and gutters for delivery into the pit for subsequent re-use in playing the game.

The invention is also characterized by the provision of a modified form in which all standing pins except those commonly designated 5, 8 and 9, are clamped upon the alley and the provision of positive means for lifting pins numbers 5, 8 and 9 or any of such pins severally, dependent upon which remains standing after the rolling of any ball but the last ball of a frame so that more space is provided for the unobstructed forward movement and more rapid operation of the pin removing or sweeping means and pins moved or swept thereby into the gutters of a bowling alley whence they are conveyed into the pit for ultimate return to the pin spotter for spotting on the alley.

Our invention is also characterized by the provision of improved mechanism for clamping standing pins on a bowling alley after the first ball of a frame is rolled and removing deadwood or fallen pins from between such clamped standing pins and also removing fallen pins and any standing pins after the last ball of a frame is rolled when it is desired to spot a new set of pins on the playing bed of a bowling alley preparatory to playing the next frame of the game.

With these and other objects not specifically mentioned in view, the invention consists in certain combinations and constructions which will be fully described hereinafter, and then set forth in the claims hereunto appended.

In the accompanying drawings, which form a part of this specification, and in which like characters of reference indicate the same or like parts:

Fig. 1 is a side elevation of a preferred form of our invention;

Fig. 2 is a front elevation taken on line 2—2 of Fig. 1;

Fig. 3 is a side elevation of a modified form of the invention;

Fig. 4 is a plan view taken on line 4—4 of Fig. 3;

Fig. 5 is a side elevation of another modified form of structure embodying our invention; and

Fig. 6 is a plan view taken on line 6—6 of Fig. 5.

While reference has been made hereinabove to the use of structure embodying our invention in connection with automatic bowling pin spotting machines, it is to be understood that the invention is also adapted for use with bowling alleys where pins are spotted manually by pin boys.

Referring to the drawings, Figs. 1 and 2 disclose a preferred embodiment of our invention adapted for use with a bowling alley designated generally A having a pit P at the end thereof. The gutters G of the alley are provided with endless belt conveyors 90 which are driven continuously, as described hereinafter, in order to convey bowling pins falling into or delivered into the gutters rearwardly into pit P where by means of conveyor 95, they are delivered to pin conveying mechanisms (not shown) which convey them to pin spotting means (not shown). In the case of manual spotting of pins on alley A, conveyor 95 would not be used since the pin boy would stand in the pit P in order that he might be able to lean forward over alley A and spot the pins thereon.

As shown in Figs. 1 and 2, there is provided a vertically reciprocating pin clamping table designated generally 10 which is suspended above alley bed A by suitable cables 12 running over and attached to suitable conventional drums (not shown). These drums are oscillated intermittently and in proper timed relation from drive control mechanism (not shown) in order that table 10 may be moved to and from the alley as desired in the course of playing the game. Table 10 is guided for up and down movement by means of guide shoes 14 mounted on the sides thereof (Fig. 2) which engage and run in suitable vertical guide rails 16 mounted on kickbacks K of the bowling alley.

Table 10 is provided with suitable bearing lugs 18 in which are journaled the ends of two longitudinally spaced horizontal shafts 20 and 22. Shaft 22 is connected by a conventional type coupling 24 (Fig. 2) to drive shaft 26 of a suitable gear reduction motor 28 mounted on the top of table 10.

Each shaft 20 and 22 carries a plurality of transversely spaced sprockets 30 aligned and so arranged that each sprocket 30 on drive shaft 22 can be connected by means of an endless chain 32 with a corresponding aligned sprocket 30 on idler shaft 20. As shown in Fig. 1, all chains 32 are parallel with the length of alley A.

Each chain 32 has pivotally attached thereto a plurality of equally spaced lugs 34 arranged along a length of chain equal to the distance between idler shaft 20 and drive shaft 22. In this way, when all lugs 34 are on the lower run of each chain 32, no lugs 34 are on the upper run (see Fig. 1), and when all lugs 34 are on the upper run of each chain 32, no lugs are on the lower run thereof.

Each lug 34 supports a rod 36 having attached to the free end thereof a flexible pusher 38, preferably made of rubber or similar resilient material. Rods 36 also are preferably made of a yieldable material, such as spring steel or plastic, which permits a springing or bending when encountering a stationary solid object such as a standing bowling pin clamped by table 10 on bowling alley A. Each lug 34 also is provided with a pivotally mounted cam follower 40 such that when a lug 34 is moving along the lower run of a chain 32, cam follower 40 engages with a straight cam track 42 formed by one flange of a channel 44 mounted on table 10 and also serving as a guide for each chain 32. As illustrated in Fig. 2, six pusher carrier chains are used. There are therefore six longitudinally extending channels spaced from each other and mounted in parallel arrangement on the bottom side of table 10. Each chain 32 is provided with four pusher rods 36, although this number could be varied if desired.

The transverse relationship of each row of rods 36 on chains 32 is such that rods 36 while being moved from the rear, or from the left, as viewed in Fig. 1, toward

the front of alley A by chains 32, normally do not engage or touch standing pins clamped on alley A, but merely pass between them. However, flexible pushers 38 attached to the free ends of each rod 36, extend laterally outwardly therefrom (Fig. 2), and deflect or yield on contact with standing clamped pins, and therefore pass such clamped pins without difficulty.

The lower or bottom side of table 10 is preferably provided with strips 46 of yieldable or resilient material such as rubber, mounted between and adjacent channels 44. Strips 46 are used to hold each standing pin engaged thereby firmly on alley A when table 10 is in its lowermost or pin clamping position, shown in full lines in Figs. 1 and 2. When table 10 is located in its upper or inoperative position during the time a player is rolling a ball, cam followers 40 on lugs 34 run on cam tracks 48 secured to the upper portion of table 10, as shown in Fig. 1. Cam tracks 48 maintain upper rods 36 substantially in the positions shown in dotted lines in Fig. 1.

Under some conditions of pin knockdown, the forward movement of pusher rods 36 in the direction of the arrows shown in Fig. 1, is sufficient to cause fallen pins to be pushed or rolled into gutters G where by means of conveyors 90, they are delivered into pit P. In order to insure that all fallen pins will be moved into gutters G for ultimate delivery into pit P, or when after a second ball is rolled it is desired to sweep standing pins from the alley, there is provided an auxiliary conveying mechanism located at the front of table 10, or at the right as viewed in Fig. 1, which has means for engaging and displacing all pins advanced forwardly by pusher rods 36 so that such pins are delivered into gutters G.

The transverse sweep mechanism, designated generally S, selected for purposes of illustration, consists of two suitably shaped coacting sweep blades 52 and 54, each of which is suspended from and secured to an endless chain 56 and 58, respectively. Chain 56, which runs on and is driven by sprocket 60, also runs on an idler sprocket 62 (Fig. 2) rotatably supported on shaft 64 having its ends journaled in transverse sweep frame 66 attached to brackets 50 which are secured to the front end of table 10. Driving sprocket 60 is rotatably supported by shaft 68, the ends of which are also journaled in sweep frame 66. A gear 70, preferably formed integrally with the hub of driving sprocket 60, engages an intermediate gear 72 which is oscillated by a gear 74 mounted on one end of a shaft 76 projecting from the housing of a suitable reversible gear reduction motor 78 mounted on the top portion of sweep frame 66. Chain 58 runs on a driving sprocket 80 and on idler sprocket 82 (Fig. 2) rotatably supported on shaft 84 mounted in sweep frame 66. Driving sprocket 80 is rotatably supported on shaft 68 and its hub is provided with a gear 86, preferably formed integrally therewith, which is oscillated by a driving gear 88 mounted on shaft 76.

In the embodiment of the invention shown in Figs. 1 and 2, pins are removed from the playing deck of bowling alley A and delivered into gutters G on continuously driven endless belts 90. Belts 90 are mounted on pulleys 92 supported on driving shaft 97 and driven shaft 99, respectively. Driving shaft 97 may be driven from any suitable source of power by conventional means (not shown). The upper runs of belts 90 are supported by suitably mounted boards 94.

The pin removing apparatus shown in Figs. 1 and 2 operates as follows: After a ball is rolled down alley A and has landed in pit P, a motor (not shown) is operated to rotate the drums which support cables 12 so that table 10 descends and its rubber cushions 46 are brought into engagement with the heads of any standing pins, thereby clamping such pins in their respective on or off-spot positions against movement. During the clamping operation, immediately after standing pins have been clamped upon the alley, the bowler presses a switch which closes a circuit through motor 28, whereupon chains 32

are moved by sprockets 30 and pusher rods 36 move from the broken line positions shown in Fig. 1 into the full line positions shown in the same figure, thereby bringing pushers 38 into engagement with any fallen pins which are moved thereby from the rear of alley A toward the front thereof and in position to be engaged and conveyed by sweep blades 52 and 54 which at the time are in back to back position at rest, as shown in Fig. 2. After all pusher carrying rods 36 have passed beneath the bottom of table 10 and have moved over the front end of table 10 to their starting positions shown in broken lines in Fig. 1, motor 28 is shut off either by an automatic timer or manually by a second button which breaks the circuit through motor 28.

When pusher rods 36 come to rest as above indicated, another button may be pushed by the operator or bowler which closes a circuit through reversible transverse sweep motor 78 causing blades 52 and 54 to move outwardly from the center of alley A toward gutters G, thus sweeping all fallen pins which were moved by pushers 38 in front of sweep blades 52 and 54. All pins delivered into gutters G by blades 52 and 54 are moved by belts 90 into pit P where they are conveyed by conveyor 95 to pin handling mechanism (not shown) which delivers them to the pin spotter. If the mechanism described herein is used in connection with manual spotting of pins, conveyor 95 will not be provided, and pins delivered into pit P will be readily available for manual spotting by a pin boy.

After sweep blades 52 and 54 reach the edge of their respective gutters G, motor 78 stops, and when another button or suitable automatic limit switch or timing device (not shown) is operated, a reversing circuit through the motor is closed, whereupon the latter drives chains 56 and 58 to return blades 52 and 54 to their rest position. The motor which lowers table 10 is then again operated either by manual control or by suitable conventional automatic control means, to raise table 10, and the alley is ready for the second ball to be rolled by the bowler.

When it is desired to remove all pins, i.e. fallen and standing pins, after the rolling of the second ball of a frame, table 10 is lowered to the position shown in broken lines in Fig. 2. At this position, designated I, standing pins will not be clamped by rubber cushions or strips 46 so that as the result of the operations of pushers 38 and sweep blades 52 and 54, all standing pins, as well as fallen pins or deadwood, will be swept from the alley and delivered by belts 90 into pit P. The means for controlling the operation of the driving means which lowers table 10 may be a control button which is pressed by the player to stop the operation of the driving motor before table 10 has been lowered to its pin clamping position shown in full lines in Fig. 2.

Figures 3 and 4 disclose a modified form of our invention. The pin removing apparatus shown comprises a table or frame designated generally 100 which is raised and lowered by cables 102 attached to brackets 104 secured to table 100. Each bracket 104 is provided with two pairs of spaced rollers 106 which roll on a vertical guide bar 108 suitably mounted on a kickback K of alley A. Cables 102 are attached to suitable drums (not shown) of a shaft (not shown) which is intermittently oscillated by a suitable source of power, such as a reversible motor (not shown). The construction and operation of the table lowering and raising mechanism may be substantially the same as that described hereinabove for the form of invention shown in Figs. 1 and 2.

Each gutter G is provided with an endless continuously driven conveyor belt 110 running on driving and driven pulleys 112, 113, respectively. Pulley 112 is driven in known manner from a suitable source of power (not shown). The upper lap of each belt 110 is suitably supported by a support board 114.

Table or frame 100 carries one pair of sweep arms 116 and 118; and another pair of sweep arms 120 and 122.

Arm 116 is mounted on a vertical shaft 124 supported in a suitable bearing bracket 126 secured to the top of table 100. Shaft 124 is provided with a sprocket 128 on which runs a chain 130 also running on a sprocket 132 fixed to a vertical shaft 134 supported in a suitable bearing bracket on the top of table 100. Sweep arm 118 is mounted on shaft 134. Shaft 134 is also provided with a beveled gear 138 which meshes with a beveled gear 140 secured to shaft 142 of a suitable reversible gear reduction motor 144. As shown in Figs. 3 and 4, motor 144 is mounted on bracket 146 secured to the top of table 100.

Sweep arm 120 (Fig. 4) is mounted on vertical shaft 148 supported in a suitable bearing bracket 150 attached to the top of table 100. Shaft 148 is provided with a sprocket 152 on which runs a chain 154 also running on a sprocket 156 mounted on vertical shaft 158 supported in a suitable bearing bracket on the top of table 100. Sweep arm 122 is attached to shaft 158. Also mounted on shaft 158 is a beveled gear 160 meshing with a beveled gear 162 mounted on shaft 164 of reversible gear reduction motor 166 supported by a suitable bracket secured to the top of table 100.

As shown in Figs. 3 and 4, sweep arms 116, 118, 120 and 122 carry a plurality of spaced downwardly projecting resilient rods 168 which are suspended from the bottom edges thereof. In the illustrated embodiment, rods 168 are formed from elongated flexible coil springs. Each rod 168 extends downwardly from its respective sweep arm through an arcuate slot formed in table 100 (see Fig. 4). Each rod 168 on its free end carries a flexible pusher 170 which extends laterally outwardly from the axis of its respective support rod 168. In the form illustrated, it will be noted that two opposing pushers 170 are interfingered in order to provide maximum sweeping range. Pushers 170 are preferably made of resilient material such as rubber or plastic in order that they may yield in passing a standing clamped pin, but also operate to move fallen pins and deadwood from the alley as the result of their movement when sweeping the alley of fallen pins or sweeping all pins from the alley when no standing pins are clamped. The under surface of table 100 is provided with a resilient clamping cushion such as rubber cushion plate 172 (Fig. 3) in order to furnish a resilient clamping action with respect to standing pins when table 100 is in its lowermost or pin clamping position shown in full lines in Fig. 3.

The pin removing apparatus disclosed in Figs. 3 and 4 operates as follows: When a bowler delivers a ball and while it is rolling along the alley towards the pins, table 100 remains in its uppermost position. Shortly after the ball lands in pit P, means (not shown) which may be under the control of the operator or bowler, are actuated to drive the motor which lowers the table 100 towards alley A until pins which remain standing are engaged by cushion plate 172 and firmly clamped against alley A. A suitable control means, such as a button of a switch (not shown) is then pressed by the bowler which completes a circuit through motors 144 and 166 which results in the movement of the opposed pairs of sweep arms 116, 118, and 120 and 122, in opposite directions or towards the right and left hand gutters G, respectively,

As the result of the movement of arms 116, 118, 120 and 122, rods 168 suspended therefrom and projecting through table 100, move through arcs and flexible pushers 170 carried by the rods, engage fallen pins and sweep them over alley A and between any pins which may be standing into gutters G where continuously driven conveyor belts 110 travel them rearwardly into pit P of alley A for further handling by automatic mechanism or for manual respotting when a pin boy is spotting pins on alley A. When rods 168 reach the points adjacent the edges of gutters G, motors 144 and 166 stop, and the operator or bowler then pushes another switch button to make a reversing circuit through these motors which

are thereby restarted and return the sweep arms 116, 118, 120 and 122 to their starting positions. Obviously limit switches may be used to accomplish the reversal of the motors 144, 166 respectively, if desired. Sweep arms 116, 120 are so designed and located that the shorter arm 116 or 120 may pass beneath its longer companion arm 118 or 122, and the speed of movement can be so arranged that both arms of a pair of arms reach the edge of their respective gutter at approximately the same time.

As in the case of the modification shown in Figs. 1 and 2, the movement of table 100 can be stopped at the elevation designated II, in which position no pins will be clamped by cushion plate 172 and hence all pins whether standing or fallen will be swept by pushers 170 from alley A into gutters G.

A further modified embodiment of the invention is illustrated in Figs. 5 and 6 wherein means are provided for gripping and lifting pins, usually designated as pins numbered 5, 8 and 9 in the customary ten pin triangular set up arrangement, prior to the operation of the sweeping means which sweeps deadwood or fallen pins from alley A after the rolling of the first ball, and which may be operated to sweep not only fallen pins, but any standing pins after the rolling of the second ball in the event that it is desired to spot ten pins on alley A.

By lifting pins 5, 8 and 9 or any pin of this group of pins which may remain standing after the rolling of the first ball of the frame, there is eliminated the need for sweeping or moving a heavy bulk of fallen pins from the rear to the front of alley A. This operation also prevents any possible entanglement of fallen pins with standing pins during the sweeping operation.

The mechanism disclosed in Figs. 5 and 6 comprises a pin clamping table 200 provided on its lower or bottom face with a resilient cushion plate 202, such as sponge rubber or like material. At each side of table 200 and extending upwardly therefrom is a bracket 204 which carries a guide shoe 206 engaging and running in a vertical guide rail 208 mounted on a kickback K. Attached to each guide shoe 206 is a cable 210, the other end of which cable is secured to a drum (not shown) mounted on a suitable motor driven shaft (not shown) adapted to raise and lower table 200. The rear portion of table 200, as shown in Fig. 6, is provided with a cut out section 212 in which is seated a pin pick-up table or frame 214. Table 214 is supported for independent vertical movement relative to table 200, by means of cables 216 which are secured at one end to brackets 218 located at each side of table 214. The other ends of cables 216 are secured to drums (not shown) on a shaft (not shown) suitably driven by a motor (not shown). Brackets 218 are provided with guide rollers 220 engaging and running in vertical tracks 222 mounted on pin clamping table 200. The bottom surface of table 214 is provided with a resilient cushion plate 224 similar to cushion plate 172 described hereinabove.

Appropriate transverse slots are formed in pick-up table 214 and cushion plate 224 through which project downwardly three pairs of arms 226, each arm supporting at its lower free end of substantially horizontal bowling pin gripping bar 228. Each arm 226 is preferably formed integrally with a operating member 230 slidably supported in a suitable track 232 (Fig. 6) formed by a groove or channel in pick-up table 214. The two operating members 230 of each pair of gripper bar arms 226 are connected by means of a pair of links 234 to a carriage or trolley 236 suspended by rollers 238 and supported by a cross bar 240 suitably attached to an actuating frame 242. A separate trolley 236 is provided for each pair of gripper bars 226.

Actuating frame 242 is secured to the upper free ends of a plurality of piston rods 244 which extend from hydraulic cylinders 246 mounted on table 214. Cylinders 246 are connected to a hydraulic control system (not

shown) which may be similar in design, construction and operation to that shown and described in Patent 2,634,979, issued April 14, 1953, to Charles E. Schon. Pick-up table 214, the pin gripper bars 228 and their operating mechanisms are generally the same in function, design and construction as those disclosed in Patent 2,634,979, and therefore a detailed description of the same is omitted in the interest of brevity.

Operating in conjunction with clamping table or frame 200 and pick-up table 214, is a sweep mechanism L designed to sweep pins from the rear to the front of alley A, and a transverse sweep mechanism S adapted to sweep pins which have been delivered by mechanism L into the range of operation of sweep mechanism S into gutters G which are provided with suitable continuously driven belt conveyors 250 operative to convey pins into the pit P of alley A for delivery to automatic pin handling mechanism, or into position where a pin boy may be able to seize and spot pins on the alley.

The mechanism for sweeping pins from the rear to the front of the alley comprises a suitable frame or truss shaped structure 252 which carries a plurality of spaced pusher bars 254 supported by a cross bar 256 attached to a pair of carriages 258 arranged to travel in any suitable manner along horizontal tracks 260 which form a part of a truss shaped structure 252 which supports pin sweeping mechanism L and moves pusher bars 254 to and from operative position relative to alley A.

Tracks 260 are secured at one end to a cross bar 262 and at their other end to a cross rod 264. Pusher bars 254 are of varying heights and are arranged with increasing height from the outer pusher bars to the center bar located in center position relative to the center of the alley. This arrangement of pusher bars creates a plow effect in sweeping and removing fallen pins. Pusher bars 254 preferably are formed of flat elastic bars, such as rubber or plastic, so that if and when a pusher bar should engage a standing pin, it will deflect relative thereto and move therewith but still engage a fallen pin and move or push it toward the front of alley A without exerting excessive and positive force upon a standing clamped pin. Each pusher bar 254 adjacent its pin engaging front end is provided with a suitably shaped shoe 266 in order to engage fallen pins and eliminate possible damage to the alley.

Carriages 258 are provided with rollers 268 so that the carriages may roll along tracks 260. The mechanism for moving the pusher bars 254 carried by the carriages back and forth relative to tracks 260 after each ball has been thrown in the form illustrated comprises a cable 270 attached to each end of each carriage 258. Each cable 270 passes over a pulley 272 mounted at the front end of frame 252 thence over a guide pulley 274 and grooved drum 276 to pulley 278 at the opposite end of said carriage. Grooved drums 276 are fixed to each end of cross shaft 280. Also secured to shaft 280 is a gear 282 (Fig. 5) which meshes with a gear 284 journaled on shaft 286 held by a suitable bracket 288 on the main frame (not shown) of the machine. Integral with the hub of gear 284 is a sprocket 290 which is driven intermittently by means of chain 292 back and forth in proper timed relation from a suitable driving source (not shown) of the machine.

The mechanism for lifting the entire pusher bar frame or truss structure 252 from and lowering the latter onto the alley may be constructed and operated in the same or similar manner to that set forth in Patterson Patent 2,313,183. As shown in Fig. 5 a rod 294 connects frame 252 to a pair of arms 296 fixed to shaft 280. Each arm 296 is connected by a suitable cable 298 to an oscillating drum (not shown) which through properly controlled driving means effects the raising and lowering of the frame 252 of sweep mechanism L. Frame 252, in addition to being connected to arms 296, is also pivotally suspended from shaft 280.

The transverse sweep mechanism S, illustrated in Figs. 5 and 6, is similar in construction and operation to that disclosed in Figs. 1 and 2, and described heretofore. This sweep mechanism is carried by bracket 300 secured to the front end of clamping table 200 and consists of two transverse sweeper blades 302 and 304, each of which is suspended from and secured to an endless chain 306 and 308, respectively. Chain 306 is supported by an idler sprocket 310 and intermittently reciprocated by a sprocket 312. Chain 308 is supported by an idler sprocket 314 and intermittently reciprocated by a sprocket 316. The latter as well as sprocket 312 are loosely supported by shaft 318 supported by a pair of suitable bearing members 320 attached to and held by the bracket 300. Idler sprockets 310 and 314 are loosely supported by shafts 322 and 324 respectively which are also supported by members 320.

The hub of sprocket 312 is integral with gear 326 which meshes with gear 328 mounted on shaft 330 of reversible gear reduction motor 332 supported by and mounted on bracket 300. The hub of sprocket 316 is integral with gear 334 which meshes with an intermediate gear 336 which in turn is driven by gear 338 mounted on shaft 330 of reversible reduction gear motor 332. Due to their operating connections with motor 332, chains 306 and 308 will be driven in opposite directions.

The operation of the mechanism disclosed in Figs. 5 and 6 is as follows: When the machine is in start position before a ball has been delivered by the bowler, the sweeper blades 302 and 304 are back to back in a central position with respect to the alley and the clamping table 200 as well as the pick-up table 214 are in their uppermost position above the alley while the pin removing mechanism L is in its upward position above the pit P. After a ball is delivered by the bowler, and has landed in the pit P, the bowler operates suitable control mechanism (not shown) to actuate the motor which lowers cables 210 and 216, whereupon clamping table 200 and pick-up table 214 move downwardly towards alley A, and both tables with their respective cushion or pressure plates engage the tops of pins which remain standing and clamp them firmly on the alley. The gripper bars 228 of the pick-up table 214 are then set in motion by means similar to those described in said Schon patent until said bars engage with the necks of the numbers 5, 8 and 9 pins in case they are, or any of them is, still standing. The operating mechanism (not shown) which is responsible for lifting table 214, is then actuated by the bowler as by pressing a button of a switch which closes a circuit through a reversible motor (not shown) which rotates a shaft (not shown) supporting drums (not shown) to which cables 216 are attached. Pick-up table 214 then moves upwardly with all or any of the pins of the group numbers 5, 8 and 9, and dwells in a position such that the bottoms of lifted pins are clear of the path of movement of sweep bars 254, which, after table 214 has reached its dwell position, move forwardly from the rear to the front of alley A during which time clamping table 200 remains in its downmost position holding all standing on or off-spot pins firmly on the alley.

After pusher bars have moved all fallen pins from the rear to the front of alley A, and delivered them in front of transverse sweeper blades 302 and 304, power is supplied either manually or automatically to motor 332, which causes blades 302 and 304 to move outwardly or transversely of alley A, whereby all fallen pins in front of them are delivered into gutters G and onto the two continuously running endless conveyor belts 250 which carry the pins received thereon into pit P of alley A where they are delivered to the pin handling mechanism (not shown) of a bowling pin spotting machine or made available to a pin boy for spotting.

After the transverse sweeper blades 302 and 304 have reached the edges of their respective gutters G, motor 332, either manually by means of a button of a switch in

the motor circuit or automatically by limit switches, is reversed. This operation effects the return of blades 302, 304 to their central back to back rest position. After pusher bars 254 of the pin removing mechanism have returned to their rearmost or starting position, frame 252 is lifted up and out of the way above pit P while the pick-up table descends again and places pins numbers 5, 8 and 9 or any of them which were lifted back on alley A in the exact position from which they were removed. Both tables 200 and 214 are then moved to a dwell position clear of all standing pins, and the machine is ready for another ball to be delivered. The upward moving operation of the tables 200 and 214 is effected by any suitable means, as by manually operated switch buttons which when pressed make circuits through the respective motors which drive the drums to which cables 210 and 216 are attached.

In the modification disclosed in Figs. 5 and 6, it may not be desired or necessary to operate pin pick-up table 214 at all times. One instance would be when pins numbers 5, 8 and 9 have been knocked down. Under such conditions, the sweeping of fallen pins is accomplished solely by means of pusher bars 254 which are operated in the manner above described.

The mechanism described hereinabove makes possible a rapid and effective removal of deadwood or fallen pins from a bowling alley after the first ball of a frame is rolled and also makes possible a similar rapid removal of all pins fallen or standing from a bowling alley whenever this is desired in the course of playing the game.

What we claim is:

1. Mechanism for removing pins arranged in generally triangular playing configuration on the playing bed section of a bowling alley comprising a pin handling device movable into engagement with pins remaining standing after a ball has been thrown, means on said device for clamping said standing pins upright on the pin supporting zone of said alley bed in their respective on or off-spot positions, means operative while said pins are clamped for moving all fallen pins along said playing bed towards the front of said alley for delivery into the gutters of said alley whereby said fallen pins are moved from the base of said triangular playing configuration toward the apex thereof to provide said pins with a substantially greater unobstructed path of travel from adjacent said clamped pins to a point of removal from said playing bed of said alley, and means operative upon pins moved toward the front of said alley to deliver them from said playing bed of said alley into said gutters.

2. The invention defined in claim 1 wherein said gutters are provided with conveying means for conveying pins delivered into said gutters into the pit of said alley.

3. The invention defined in claim 1 wherein pins are moved by said second named means to a delivery station in front of said zone, and wherein said means operative to deliver said pins into said gutters includes transversely movable conveying means operative to move pins from said zone into said gutters of said alley.

4. The invention defined in claim 3 wherein said gutters are provided with continuously movable conveying belts for delivering pins received thereon into the pin of said alley.

5. A pin sweeping apparatus for use with a bowling alley having a pin supporting bed section comprising a table adapted to be moved to and from a position above the pin supporting bed of said alley into position to clamp and hold standing pins in their respective on and off-spot positions on said bowling alley bed after the rolling of a ball, a plurality of pin removing pushers mounted on said table, means mounting said pushers for movement along said pin supporting bed section from the rear toward the front thereof, means for moving said pushers from the rear toward the front of said pin supporting bed section to engage and travel fallen pins towards the front of said pin supporting bed section and

clear of any clamped standing pins, drive means for said last-named means, an auxiliary pin conveying mechanism mounted on said table, said mechanism comprising transversely moving conveying elements, and means for moving said elements away from each other to convey pins delivered into the range of operation of said elements by said pushers into the gutters of said bowling alley for delivery into the pit of said alley.

6. In a pin clearing apparatus for use with a bowling alley to remove pins from the playing bed of a bowling alley, a table adapted to be moved to and from a position above the pin supporting bed of said alley into position for clamping standing pins on said bowling alley bed after the rolling of a ball, a plurality of laterally spaced endless conveyors carried by said table, a plurality of longitudinally spaced pin removing pushers mounted on each of said conveyors, means mounting said conveyors on said table for movement of said pushers along said pin supporting bed from the rear toward the front thereof, means for travelling said conveyors from the rear toward the front of said playing bed to move said pin removing pushers from the rear toward the front thereof and into engagement with pins to be removed from said alley and to convey said pins forwardly up said alley to the front of said pin supporting bed and clear of any clamped supporting pins, drive means for said last named means, and means operative upon pins moved toward the front of said pin supporting bed to deliver them from said bed into the gutters of said bowling alley.

7. The invention as defined in claim 1 wherein said means for moving fallen pins toward the front of said alley and said delivery means include mechanism operative while said pins are clamped for engaging and moving all fallen pins in arcuate paths toward the front of said alley and into the gutters of said alley.

8. The invention defined in claim 7 wherein said mechanism comprises opposed sets of sweep arms, spaced resilient rods depending from said arms through slots in said table, flexible pushers carried by said arms, and means for operating said arms to move said pushers into engagement with pins to be swept from said alley.

9. The invention defined in claim 7 wherein said mechanism comprises opposed sets of arms, depending pushers carried by said arms, and means for moving said arms through arcuate paths of travel to engage said pushers with pins to be removed from said alley and deposit said pins in the gutters of said alley.

10. The invention defined in claim 9, wherein said gutters are provided with continuously movable conveying belts for delivering pins received thereon into the pit of said alley.

11. The invention defined in claim 7 wherein said pin handling device is provided with a plurality of slots and said mechanism includes a plurality of sweep arms, means mounting said sweep arms for movement in opposite directions from and to each other, a plurality of depending rods carried on each of said sweep arms, a flexible pin pusher mounted on each of said rods, means for moving said arms away from each other to move unwanted pins off said alley bed into the gutters of said alley and means for delivering pins deposited by said pushers in said gutters into the pit of said alley.

12. The invention defined in claim 1 including a carriage associated with said pin handling device, a plurality of spaced pusher members each having one end connected to said carriage, and means for moving said carriage relative to said table to travel said members forwardly beneath said table into engagement with fallen pins, whereby in response to the movement of said members said fallen pins are transported from beneath said table and said alley bed section to a point of delivery in front of said bed section.

13. The invention defined in claim 12, including a conveying mechanism, said mechanism comprising pusher elements for moving pins from said point of delivery

across said bowling alley into the gutters thereof for delivery therefrom into the pit of said alley.

14. The invention defined in claim 12, wherein said pin handling device comprises a vertically movable auxiliary pin gripping and lifting table, a plurality of pin gripping units carried by said auxiliary table adapted to engage and lift any standing pins on pin spots 5, 8 and 9 of said alley bed section, and means for operating said gripping units to grip and hold any of said last-named pins standing during the lifting movement of said auxiliary table and the operation of said spaced pusher members, and means for moving said auxiliary table to return pins lifted thereby to their respective on and off-spot positions.

15. In a pin clearing apparatus for use in removing unwanted pins from the playing bed of a bowling alley, a table adapted to be moved to and from a position above the pin supporting bed of said alley into position for clamping standing pins on said bowling alley bed after the rolling of a ball, a plurality of sets of laterally spaced pin removing pushers mounted on said table including movable supports for said pushers, means for moving said supports from the rear of said playing bed toward the front thereof to move said pushers between clamped standing pins and push fallen pins to the front of said pin supporting bed clear of said clamped standing pins and means operative upon pins moved toward the front of said pin supporting bed to remove them from said bed of said bowling alley.

16. A pin sweeping apparatus for use with a bowling alley having a pin supporting bed section comprising a table adapted to be moved to and from a position above the pin supporting bed of said alley into position to clamp and hold standing pins in their respective on and off spot positions on said bowling alley bed after the rolling of a ball, a plurality of pin removing pushers, means mounting said pushers for movement along said pin supporting bed section from the rear toward the front thereof, means for moving said pushers from the rear toward the front of said pin supporting bed section to engage and travel fallen pins towards the front of said pin supporting bed and clear of any clamped standing pins, driving means for said last named means and means operative upon pins moved toward the front of said pin supporting bed to deliver them from said bed into the gutters of said bowling alley.

17. In a pin clearing apparatus for use with a bowling alley to remove pins from the playing bed of a bowling alley, a table adapted to be moved to and from a position above the position of a pin supporting alley into position for clamping standing pins on said bowling alley bed after the rolling of a ball, a plurality of laterally spaced endless conveyors, a plurality of longitudinally spaced pin removing pushers mounted on each of said conveyors, means mounting said conveyors on said table for movement of said pushers along said pin supporting bed from the rear to the front thereof, means for travelling said conveyors from the rear toward the front of said playing bed to move said pin removing pushers from the rear toward the front thereof and into engagement with pins to be removed from said alley and to convey said pins forwardly up said alley to the front of said pin supporting bed and clear of any clamped standing pins, an auxiliary pin conveying mechanism mounted on said table, said mechanism comprising transversely movable conveying elements and means for moving said elements away from each other to convey pins travelled into the gutters of said bowling alley for delivery into the pit of said alley.

18. In a pin clearing apparatus for use in removing pins from the playing bed of a bowling alley, a table adapted to be moved to and from a position above the pin supporting bed of said alley into position for clamping said pins onto said bowling alley bed after the rolling of a ball, a plurality of laterally spaced endless conveyors,

a plurality of longitudinally spaced pin removing flexible pushers mounted on each of said conveyors, means mounting said conveyors on said table for movement of said pushers along said pin supporting bed from the rear toward the front thereof, means for travelling said conveyors from the rear toward the front of said playing bed to move said pushers into engagement with pins to be removed from said alley and to convey said pins forwardly up said alley to the front of said pin supporting bed and clear of any clamped standing pins, drive means for said last-named means, and means operative upon pins moved toward the front of said pin supporting bed to remove them from said bed of said bowling alley.

19. In a pin clearing apparatus for use in removing unwanted pins from the playing bed of a bowling alley, a table adapted to be moved to and from a position above the pin supporting bed of said alley into position for clamping standing pins on said bowling alley bed after the rolling of a ball, a plurality of laterally spaced endless conveyors, a plurality of spaced resilient rods fixed to said conveyors, a flexible pin removing pusher mounted on each of said rods, means mounting said conveyors on said table for movement of said pushers along said pin supporting bed from the rear to the front thereof, means for moving said conveyors from the rear toward the front of said playing bed to travel said pin removing pushers into engagement with pins to be removed from said alley and to convey said pins forwardly up said alley to the front of said pin supporting bed clear of any clamped standing pins, drive means for said last-named means, an auxiliary pin conveying mechanism mounted on said table, said mechanism comprising transversely movable conveying elements and means for moving said elements away from each other to convey pins delivered into the range of operation of said elements by said pushers into the gutters of said bowling alley for delivery into the pit of said alley.

20. In a bowling pin spotting machine having mechanism for positioning bowling pins in generally triangular standing playing configuration on the playing bed of a bowling alley, mechanism for removing pins from the playing bed of said alley, said alley having a pit adjacent said bed comprising a pin handling device movable into engagement with pins remaining standing on the playing bed of a bowling alley after a ball has been thrown, means on said device for clamping said standing pins upright on said pin supporting bed of said alley in their respective on or off spot positions, means operative while said pins are clamped by said device on said alley bed for sweeping all fallen pins in a generally forward direction away from the pit of said bowling alley whereby said fallen pins are travelled from the base of said triangular configuration adjacent said pit toward the apex of said triangular configuration remote from said pit to provide said fallen pins with a substantially wider unobstructed path of travel adjacent said clamped pins to a point of removal from said playing bed of said alley and means positioned to receive pins delivered thereto by said last-named means and deliver them into the pit of said alley.
